UNITED STATES PATENT OFFICE

150,893

DESIGN FOR A HANDBAG OR SIMILAR ARTICLE

Jerome S. Singer, New York, N. Y.

Application November 4, 1947, Serial No. 142,299

Term of patent 14 years

(Cl. D87—3)

To all whom it may concern:

Be it known that I, Jerome S. Singer, a citizen of the United States of America, residing in New York city, county of New York, and State of New York, have invented a new, original, and ornamental Design for a Handbag or Similar Article, of which the following is a specification, reference being had to the accompanying drawing, forming part thereof, wherein:

I claim:

The ornamental design for a handbag or similar article, substantially as shown.

JEROME S. SINGER.
